UNITED STATES PATENT OFFICE.

IRA A. BURNETT, OF CHICAGO, ILLINOIS.

MOISTENING ATTACHMENT FOR DENTAL-ENGINE HANDPIECES.

1,345,579.

Specification of Letters Patent.

Patented July 6, 1920.

Application filed May 1, 1920. Serial No. 378,043.

To all whom it may concern:

Be it known that I, IRA A. BURNETT, a citizen of the United States, residing at Chicago, in the county of Cook and State of Illinois, have invented certain new and useful Improvements in Moistening Attachments for Dental-Engine Handpieces, of which the following is a specification.

My present invention relates to improvements in moistening attachments for dental engine hand pieces of a type similar to that disclosed in Letters Patent 1,318,351, issued to me on October 14, 1919, and has for one of its objects to greatly improve the construction and efficiency of such attachments made according to my aforesaid Letters Patent, and to provide a moistening attachment which shall be more compactly constructed than that set forth in my said Letters Patent, or so made at its operative end as to obstruct the vision of the operator to a less extent than has heretofore been accomplished by devices of a like character.

Further objects and advantages of the invention are similar to those set forth in my aforesaid Letters Patent, and are as follows: To provide an extremely simple and inexpensive moistening attachment for dental engine hand pieces, which can be instantly attached thereto or removed therefrom, and of such construction and arrangement of its parts that water in the desired quantities can be supplied in drops or jets (as may be desired), to the grinding disks or stones, burs, drills and the like, for the purpose of keeping the same cool or reducing their temperature.

Another object is to so construct the attachment that when applied to the hand piece it will fit the same in such a way as to prevent water from entering the said piece, and thereby causing corrosion or rusting of its parts.

Other objects and advantages of the invention will be disclosed in the following description and explanation.

In the accompanying drawing, which serves to illustrate an embodiment of the invention—

Figure 1 is a plan view of a dental engine hand piece and its mount, showing one form of my improved moistening attachment for the hand piece mounted in operative position thereon.

Fig. 2 is a view in side elevation of like

parts but showing the attachment in longitudinal section.

Fig. 3 is a bottom plan view of similar parts to those shown in Figs. 1 and 2 but illustrating a slight modification in the construction of the attachment, and

Fig. 4 is an enlarged sectional view taken on line 4—4 of Fig. 3 looking in the direction indicated by the arrows.

Like numerals of reference refer to corresponding parts throughout the different views of the drawings.

The reference numeral 6 designates the dental engine hand piece, which may be made of the well known or standard construction, the front end of which is provided with a forwardly tapered and centrally apertured head 7 in which the mandrel or shaft 8 of the tool operated by the engine is located and may be held in the customary manner.

In Fig. 1 the mandrel is shown as being provided with a grinding stone 9 and in Figs. 2 and 3 said mandrel is shown as being provided with a grinding disk, but it will be understood that other kinds of tools, such as burs, drills, and the like may be employed. A sleeve or tubular member 10, having internal screw-threads in the rear portion of its cavity is mounted at the front end 80 of the head 7 of the hand piece, which head terminates at its free end abruptly or with an end wall 11 disposed at a right angle to the axial line of said head.

Located longitudinally with respect to the sleeve or tubular member 10 and merged therewith is a water delivery tube 12 which has its front portion reduced and extended slightly in front of the reduced front portion 13 of the member 10 as is clearly shown 85 at 14 in Figs. 1 and 2 of the drawings, to which views the above description is particularly directed.

In Fig. 2 it will be clearly seen and readily understood that in the construction illustrated in said figure as well as in Fig. 1, the water delivery tube 12 has an independent passageway from that of the member or sleeve 10, and that said delivery tube is extended rearwardly from the upper portion 100 of the member 10 and is provided near its rear end with a pair of curved jaws or clamping members 15 which are adapted to stride and clamp the body of the hand piece 105 some distance rearwardly of its head. The 110

water delivery tube 12 is also provided between the jaws 15 and the head 7 with a pair of curved clamping jaws 16 adapted to stride and clamp a portion of the hand piece 5 nearer its head in order to more firmly secure the attachment in place against the latter.

By reference to Fig. 2 it will be seen that the rear portion of the sleeve or member 10 has located therein a sleeve 17 which by preference is made of rubber, but may be made of any suitable resilient material. This sleeve is provided centrally and longitudinally with an opening 18 through which 10 the mandrel 8 is extended into the front end of the hand piece 6 where it will be engaged by a chuck carried by said hand piece, which chuck is not shown but may be of the ordinary or usual construction. The tubular member 10 is by preference provided in the rear portion of its cavity with screw-threads 15 in order that the orificed sleeve 17 may be screwed therein and held against rotation, but it will be understood that I do not wish 20 to be limited to such construction as the member 17 may be otherwise secured in said tubular member. When located in its operative position the outer or rear end of the member 17 will be located about flush with 25 the rear end of the tubular member 10 while the inner end of the resilient member 17 will rest against the inner surfaces of the walls of the member 10 and thus will be prevented longitudinal movement, and so held by the 30 clamps or jaws 15 and 16 that it will rest against the front end of the tapered head 7 and closely around the mandrel 8 in such a manner as to exclude the possibility of water discharged from the delivery tube 12 35 against the tool carried by the mandrel working or passing back into the hand piece and thereby causing its internal parts to be impaired by rust or corrosion.

The rear end of the water delivery tube 40 12 is by preference provided with an annular enlargement 19 over which is fitted a flexible tube 20 leading to a compressible hand bulb 21 containing water, and which can be conveniently held in the palm of the 45 hand of the operator while the instrument may be held with the thumb and forefingers applied to the attachment at about its juncture with the front end of the hand piece and properly manipulated with but little obstruction to his vision by reason of the compact form of the front portion of the attachment produced by merging the 50 delivery tube 12 with the member 10.

In Figs. 3 and 4 of the drawings is shown 55 a modification in the construction of the attachment, which consists in providing the front end of the tubular member 10 with one or more cut-away portions 22 or slits and in uniting the passageway 23 with the 60 passageway 24 of the member 10 rear-

wardly of the front end of the latter, instead of making said passageways independent of each other as in the construction illustrated in Figs. 1 and 2 and above described. Otherwise, the attachment is of 70 the same construction as that shown in Figs. 1 and 2 and above described.

From the foregoing and by reference to the drawing, it will be readily understood and clearly seen that when the parts are assembled as shown in Figs. 1 and 2 and 3, and as above described, water may be ejected from the bulb 21 through the tube 20 and water delivery tube 12 against the grinder or tool 9 carried by the mandrel in the desired quantities by simply compressing the bulb, which as before stated, may be carried in the palm of the hand, that is used for operating the hand piece, and that by reason of the closure provided by the sleeve 80 17 water will be absolutely prevented entering the hand piece.

In the construction shown in Figs. 1 and 2 the front and reduced portion 14 of the water delivery member 12 projects a slight 90 distance forwardly of the front end of the member 10 so as to almost contact with the stone 9 or other tool, thereby affording means for applying water directly to the tool and without danger of dripping off at 95 the free end of the reduced portion of the water delivery tube as might occur if the same were not forwardly extended as set forth.

The modified construction shown in Figs. 100 3 and 4 has been found particularly useful in affording means for directly discharging water from the delivery tube to the tool in instances where the mandrel 8 is rearwardly tapered adjacent the tool, and fits so closely 105 within the reduced front portion 13 of the member 10 as to prevent the discharge of water. By providing the front end of the reduced portion 13 with the spaced apart slits or cut-out portions 22, it is evident that 110 the above mentioned objection or difficulty will be overcome.

In the drawings the hand piece is shown in connection with a mount or portion 25 of the engine, which of course forms no part 115 of the present invention, and need not be herein described.

Having thus fully described my invention, what I claim as new and desire to secure by Letters Patent is—

1. In a moistening attachment for dental engine hand pieces, the combination with a tubular member, of a resilient sleeve located in the rear portion of said member and adapted at its rear end to contact with the 125 front end of said hand piece, said sleeve having a longitudinal opening registering with the opening in the hand piece and with the opening of the tubular member in which it is located, and means longitudinally 130

mounted on said tubular member and extended along the same for the discharge of water at its front portion near the front end of said tubular member.

- 5 2. In a moistening attachment for dental engine hand pieces, the combination with a tubular member, of a resilient sleeve located in the rear portion thereof against rotation and adapted at its rear end to contact with

the front end of said hand piece, said sleeve 10 having a longitudinal opening registering with the opening in the hand piece and with the opening in the tubular member in which it is located, and a water delivery conduit located longitudinally on and with respect 15 to the tubular member and merged therewith at its front portion.

IRA A. BURNETT.
